UNITED STATES PATENT OFFICE.

CHARLES WOOD DAVIS AND MORTON R. DAVIS, OF PEOTONE, KANSAS.

DESIGN FOR A GANG-FRAME FOR CULTIVATORS.

SPECIFICATION forming part of Design No. 28,747, dated May 31, 1898.

Application filed May 27, 1897. Serial No. 638,476. Term of patent 14 years.

To all whom it may concern:

Be it known that we, CHARLES WOOD DAVIS and MORTON R. DAVIS, citizens of the United States, and residents of Peotone, Viola township, in the county of Sedgwick and State of Kansas, have invented and produced a new and original Design for a Gang-Frame for Cultivators, of which the following is a specification, reference being had to the accompanying drawing, forming a part thereof.

The drawing is a top plan view of a gang-frame for cultivators showing our new design.

As shown in the drawing, the leading or material feature of our design consists in a frame having a hexagonal border, short longitudinal end projections, and body-bars, whereby the opposite sides of the frame are divided longitudinally.

The gang-frame is hexagonal or six-sided, having ends projecting longitudinally therefrom and body-bars extending parallel with and intermediate of the opposite sides and ends. 20

Having thus described our invention, the following is what we claim as new therein and desire to secure by Letters Patent:

The design for a gang-frame for cultivators substantially as herein shown and described.

CHARLES WOOD DAVIS.
MORTON R. DAVIS.
